SORTING MACHINE

Rudolf Lorant, Berlin-Dahlem, Germany, assignor, by mesne assignments, to International Business Machines Corporation, New York, N. Y., a corporation of New York

Application May 12, 1932, Serial No. 610,863

5 Claims. (Cl. 209—110)

This invention relates to machines for sorting perforated records such as, for instance, the perforated record cards used in the well known Powers or Hollerith systems of compiling account 5 and statistical data.

The primary object of the invention is to provide a sorting machine of the type above described which is more universal in its applications, that is to say, to provide a sorting machine 10 capable of performing more functions than former machines.

More specifically stated, the invention provides a machine which is capable not merely of simple sorting of record cards into separate pockets according to the index-point values of the control 15 perforations and simple selective sorting according to one or more pre-determined index-point perforations but is also capable of such operations as those of selecting paired cards, selecting 20 falsely perforated cards, selecting whole groups of related cards as a unit, replacing certain cards in a batch by new cards, removing pre-determined cards from a batch, and, carrying out, during a single passage of the cards through the machine, 25 the function of replacing certain cards by others and the function of removing predetermined cards from the batch.

A more specific object is to generally improve sorting machines of the type disclosed in United 30 States Letters Patent No. 1,741,985 granted December 31, 1929 to E. A. Ford by providing such machines with means permitting the aforesaid machine to perform the additional functions given in the preceding paragraph.

35 Various other objects, features or advantages of the invention will be pointed out in the following specification and claims or will be apparent after a study of said specification and claims and the accompanying drawings.

40 Figure 1 is a circuit diagram illustrating the invention.

Figure 2 is a chart showing the timing of certain commutators illustrated diagrammatically in Figure 1.

45 Figure 3 is a diagrammatic view showing the arrangement and feeding of a batch of cards from which paired cards are to be selected and placed in a common sorting pocket separate from the single or unpaired cards.

50 Figure 4 is a view similar to Figure 3 showing the arrangement of the same batch of cards shown in said figure when the cards of the pairs are to be sorted into two separate sorting pockets.

55 Figure 5 is a view similar to Figure 3 showing the arrangement of a batch of cards wherein cer-

tain falsely perforated cards appear which it is desired to remove automatically.

Figure 6 is a view similar to Figure 3 showing the arrangement of a batch of cards wherein certain cards are to be replaced by others.

Figure 7 is a view similar to Figure 6 and illustrates the arrangement of the same batch of cards shown in said figure when certain of the cards are to be removed and others replaced during a single passage of the batch through the machine.

Figure 8 is a view similar to Fig. 3 showing the arrangement of a batch of cards when whole groups of cards are to be removed.

I. Sorting mechanism

The sorting mechanism may be of any desired construction, but is preferably of the form illustrated and described in Letters Patent 1,741,985, cited hereinbefore, consequently only a brief description of said mechanism will be given herein and for further details reference may be had to the patent.

The numerals 20 refer generally to a series of flexible blades whose right ends (Fig. 1) lead to different sorting pockets (not shown) of which there are usually thirteen and whose left ends are narrowed and curved upwardly as shown in Figure 1. The curved or upturned ends rest normally upon the armature 21, which comprises a narrow plate normally occupying a position flush with and between two fixed parallel guide plates 22. Cooperating with the armature 21 is the sorting magnet SM.

The cards to be sorted are fed from a hopper (not shown) mounted to the left of the blades 20 and are fed by any suitable feeding mechanism such as the one shown in above patent. A suitable card picker (not shown) advances the lowest card in the hopper toward the feeding rolls (not shown) which carry the card between the main sorting brush B-1 and a contact roll CR, the card 24 thus advanced passing over the top surface of the plates 22 and beneath the upturned ends of blades 20. The brush B-1 is the normal sorting brush of the machine and is mounted in a movable brush holder as described in the above patent, which brush holder may be moved manually to bring the brush B-1 into position to sense holes in any desired column of index points in the record cards advanced by the feeding mechanism. Cooperating with the contact roll CR is a pair of feed rolls 23, only one of which is shown, Fig. 1, whose purpose is to hold the card in contact with the contact roll CR and also to feed the card to the right, Fig. 1.

The brush B-2 is in a series circuit extending from said brush through the normally closed contacts of a relay R-4, the windings of relays R-1, R-2, and the sorting magnet SM, and the lower 5 normally closed contacts of relay R-3 to the right line wire 25. The contact roll CR has a common contact brush CB which is connected to the left line wire 26 through a commutator C-5 (shown diagrammatically in Fig. 1), which commutator 10 is similar in construction to the commutator described in the above patent. The purpose of the commutator C-5 is to permit sorting in accordance with predetermined index points and operates exactly as described in the patent cited. It 15 will be understood that said commutator C-5 is provided with twelve positions or bars any one or all of which may be made current conducting with the left line wire 26 in the manner described in the above patent.

20 When it is desired to carry out selective sorting operations as, for instance, to select from a given batch all cards having a perforation in the "7" index-point position of a predetermined column of the record cards the bar of commutator C-5 corresponding to the "7" index point position will be made current conducting with the line wire 26. When the machine is started as described in the patent cited, cards will be advanced by the feeding mechanism past the brush B-1 25 and the contact roll CR and if the brush B-1 senses a hole in the "7" index-point position of the desired column in any card a circuit will be established as follows: Left side of line 26, the "7" position or bar of commutator C-5, the brush 30 CB, contact roll CR, brush B-1, normally closed contacts of relay R-4, the windings of relays R-1 and R-2, the sorting magnet SM and the normally closed lower contacts of relay R-3, to the line wire 25.

35 Energization of the magnet SM will occur at the time when the right edge (Fig. 1) of the card lies between the appropriate blade 20 leading to the "7" pocket and the next adjacent blade on the left (Fig. 1) leading to the "6" pocket so that the armature 21 will be drawn downwardly thereby lowering the blade 20 corresponding to the "7" sorting pocket and all other blades immediately to the right of said blade, while the blades 20 to the left of the "7" blade will be held up by the surface of the card. As a result the card having the hole in the "7" index-point position will be guided into the space between the "6" and "7" blades and then will be carried by suitable feeding rolls (not shown) to the right into the "7" pocket. Any succeeding cards which have a perforation in the "7" index-point position will likewise be guided by the "6" and "7" blades 20 into the "7" pocket. All other cards having no hole in the "7" index-point position of the column from which sorting is being controlled will pass beneath the upturned ends of all blades 20 without causing the magnet SM to be energized and will be conveyed into the "reject" pocket or "R" pocket as it is usually called.

40 Energization of the relay R-1 causes it to close its contacts and thereby establishes a holding circuit for itself, relay R-2, and the sorting magnet SM through the commutator C-1 which holding circuit is maintained until the brush B-1 45 has finished sensing the "12" index-point position in the card, whereupon the commutator C-1 breaks the circuit through the relays R-1, R-2 and the sorting magnet SM (see Fig. 2). During normal sorting operations the relay R-2 will 50 attract its armature, however closure of the nor-

mally open contacts associated with the relay R-2 will have no effect since the circuit which this relay controls is kept open by suitable switches. The functions of the relays R-2, R-3, and R-4 will be more fully described hereinafter in connection with the various sorting operations of which machine is capable.

55 The normally opened contacts of relay R-2 are connected to one of a pair of brushes 27 co-acting with commutator C-2, which is so arranged as to connect the brushes 27 electrically from a point somewhat beyond the "12" index-point position to a point between the "7" and "8" index point positions of the following cycle as shown in Fig. 2. The other brush 27 is connected to the common terminal of a three-point switch S-1, the lower point of which is connected through a resistance to the left line wire 26, while the upper point is connected directly to said line wire.

90 In shunt across brushes 27 and in series with a switch S-2 is the winding of relay R-4. For normal sorting operations, the switch S-1 is set in the middle position so that the energization of the relay R-2 and closure of its associated contacts has no effect.

95 Connected in shunt with the sorting magnet SM and a pair of brushes 28 through a switch S-3 is a commutator C-3, which is arranged to electrically connect the brushes 28 from a point between the "2" and "3" index-point positions of a given cycle to a point just beyond the "12" index-point position of the same cycle, as shown in Fig. 2. The switch S-3 is open during normal sorting operations so that commutator C-3 has no effect upon the sorting magnet.

100 Extending from the brush B-1 is a series circuit including a pair of brushes 29 associated with a commutator C-4 arranged to connect the brushes 29 electrically from the "8" index-point position to the "3" index-point position of the same cycle as shown in Fig. 2, which series circuit extends through the winding of a relay R-3, a resistance, and a switch S-4 to the right line wire 25. The switch S-4 is open during 105 normal sorting operations so that the relay R-3 ordinarily has no effect, hence the lower contacts of said relay will remain closed.

110 The commutators C-1 to C-5, inclusive, are preferably mounted on a common shaft and are 115 driven in synchronism with the feed rolls 23 so that each commutator makes one revolution per card cycle and establish circuits according to the timing just described and illustrated in Fig. 2 wherein the solid black portions represent the 120 part of the cycle during which the circuit is closed through each individual commutator. The functions of these various commutators and 125 relays will now be explained in detail with reference to a series of diagrammatic figures which 130 illustrate the arrangement of the cards in a batch for accomplishing the various functions referred to hereinbefore.

II. Sorting paired cards into a pocket separate from the pocket for the single cards

135 It is desired at times to select from a given batch of cards all those cards which are paired and have common data thereon as, for instance, in selling goods a card may be punched when the invoice is made out and the goods shipped and later a second card may be punched when the invoice is paid. The problem is to sort out from a miscellaneous batch of cards those pairs of cards representing the invoice and the pay- 140

ment of such invoice. In order to do this the cards which represent a paid invoice are provided with a perforation in the "12" index-point position of a given column, whereas in the corresponding column of the card first made out for the invoice there is no "12" perforation provided. It is necessary to carry out a preliminary sorting operation to place the cards in numerical order according to invoice or group number so that those cards which are paired will come together, thereafter the cards will again be passed through the machine and the pairs selected and sorted into a pocket separate from the pocket for the unpaired cards.

15 The new cards having the "12" holes representing paid invoices are placed in the hopper of the machine and the first sorting run carried out until all the cards are exhausted. The old cards having no "12" holes are representing the 20 invoices are then placed in the hopper and the first sorting run continued until the old cards are exhausted. The remaining sorting runs necessary to bring the cards into numerical order are then completed using the batch of combined 25 cards. Usually the first run sorts the cards according to the units place of the group number, then sorting on the tens place is carried out and so on until all decimal positions of the group number have been sorted into proper order.

30 It will be found after this preliminary sorting operation has been completed that the cards having the "12" perforations will lie on top of the corresponding cards which have no perforations in the same column. In other words each 35 card representing a paid invoice will be immediately followed by the card made out for that same invoice when the goods were shipped.

The problem is now to select all the cards which are paired off and in order to do this the cards 40 are placed face down in the hopper of the machine so that the edges of the cards in which the "12" perforations appear will pass under the brush B-1 first as the cards are fed from left to right (Fig. 1) in numerical order. In other 45 words, the "12" holes in the cards representing paid invoices will be sensed as "9" holes by the brush B-1. The switch S-3 will be opened while the switch S-1 will be shifted to the lower position (Fig. 1) so that the resistance connected 50 to the lower position of said switch will be connected in series with brushes 27 to the normally open contacts of relay R-2. The switch S-2 will remain open. The sorting brush B-1 is positioned to sense the cards in the column 55 in which the "12" perforation occurs.

Fig. 3 indicates diagrammatically the order in which the cards are fed and their arrangement in the batch. It will be understood that in Fig. 3 the cards are fed face downwardly in the direction of the straight arrows toward the brush B-1 in such fashion that the "12" index-point positions are sensed first and the "9" index point positions last. In other words the usual order for sensing the cards is reversed as normally the "9" 60 positions are read first and the "12" positions last.

The relative arrangement of the cards will be clearly evident in Fig. 3 and following figures by noting the position of the cut corners in the cards. Normally the upper left hand corners are cut 65 from the cards in order to ensure that the cards will always be stacked properly. It is not necessary that the corners be cut in order to sort successfully but the cut corners are convenient as they provide a means indicating that all cards 70 are face up.

Before placing the cards in the hopper it is necessary to place a blank card in the hopper so that the blank card will be the first card fed. The purpose of this blank card is to insure that the machine will be in readiness to properly select the 80 paired from the single cards as, due to the arrangement of the circuits for the pairing operation, it is possible that the machine may have stopped after a prior sorting operation with the sorting magnet energized in which case the first card would go to the "9" pocket. The blank card will, of course, be fed from the hopper first and will pass beneath the brush B-1 into either the "9" pocket or the "R" pocket depending upon the stopping point of the machine after the last sorting operation.

In Fig. 3 the cards marked with the letter "P" and accompanied by a numeral are the cards representing a paid invoice, the numeral representing the group number identifying the invoice or the 90 customer as the case may be. The card immediately following a card designated with a "P" represents the invoice made out when the goods were shipped. In Fig. 3 those cards which are pairs are designated by curved double headed arrows, 95 whereas the single unpaired cards are not designated, thus the cards designated P-1, 1, P-3, 3 and P-4, 4 are paired. The cards 2 and 5 to 7, inclusive, represent single invoices which have 100 not been paid.

It will be noted that the "P" cards have "12" holes in a given column or position on the card, whereas the single cards have no such hole nor, in fact, any hole in the corresponding column. When the card P-1 is sensed by the brush B-1 110 the "12" hole appearing in the P-1 card will be read as if it were a "9" hole and, assuming that the commutator C-5 has been rendered current conducting in the "9" position only, a circuit will be established as follows: Left side of line 26, the 115 "9" position of the commutator C-5, common brush CB, contact roll CR, brush B-1, the normally closed contacts of relay R-4, windings of relays R-1 and R-2, sorting magnet SM, and the lower contacts relay R-3, to the right side of 120 the line 25. The sorting magnet SM will attract its armature lowering all the blades 20 and thereby causing the P-1 card to be guided into the "9" pocket.

Energization of the relay R-1 will set up a 125 holding circuit for itself, relay R-2, and sorting magnet SM through the commutator C-1 which holding circuit will be maintained until the brush B-1 has traversed all the index-point positions of the P-1 card. Energization of the relay R-2 130 eventually sets up a second holding circuit through the brushes 27 and switch S-1 to the line 26.

The commutator C-2 becomes effective just beyond the "12" position so that, when the commutator C-1 breaks the holding circuit for relay R-1, the holding circuit through the relay R-2 and sorting magnet SM will still be maintained through the beginning of the next cycle. Consequently the sorting magnet will still be energized 135 when the next card (the "1" card) is fed past the brush B-1 and the contact roll CR, thereby causing said "1" card to be likewise guided into the "9" pocket. Commutator C-2 will break at the "8" index-point position of the cycle in which the 140 brush B-1 is passing over the "1" card, thereby causing the sorting magnet SM and the relay R-2 to become deenergized. It will be seen, therefore, that the first pair of cards P-1, 1 will be conveyed into the "9" pocket. 145

The card designated 2 is a single card having no accompanying "P" card and has no hole in the column traversed by the brush B-1, consequently said card will pass to the reject or "R" pocket, 5 since the sorting magnet is deenergized and cannot be again energized owing to the absence of a hole in the column read by brush B-1.

When the second pair of cards P-3, 3 is sensed by the brush B-1, said cards will likewise be conveyed to the "9" pocket in exactly the same fashion as the cards P-1, 1 were conveyed to said pocket, 10 since the occurrence of the "12" hole in the P-3 card will set up the successive holding circuits through the commutators C-1, C-2 as before 15 and energize the sorting magnet SM at the "9" index-point position of the cycle for the P-3 card and the sorting magnet will remain energized until the "8" index-point position of the cycle in which the 3 card is sensed by the brush B-1.

20 It will be seen, therefore, that those cards which are paired will be conveyed into the "9" pocket, whereas the single unaccompanied cards will be conveyed into the reject pocket.

In actual practice the "P" cards will be provided with some physical characteristic which clearly indicates their nature as by a color stripe, an over printed letter or word, or they may be colored differently from the cards which they are paired.

30 *III. Sorting paired cards into two pockets separate from the pocket for the single cards*

It is sometimes desired to sort the paired cards so that the corresponding cards of the pairs fall 35 into two pockets separate from the pocket for the single cards. This operation may be very readily performed according to the present invention by placing the batch of cards illustrated in Figure 3 in the machine face down so that the cards are 40 fed in the usual fashion with the "9" index-point positions sensed first by the brush B-1. Fig. 4 illustrates the same batch of cards shown in Fig. 3 fed towards the brush B-1, in the normal 45 fashion, said brush, as before, reading the columns in which the "12" holes appear in the "P" cards.

The commutator C-5 in this case is made current conducting in the "12" position only and the arrangement of circuits is the same as when the 50 paired cards are sorted into a single pocket instead of into separate pockets as in the present case, that is, the switch S-2 will be opened and the switch S-1 in the lower position. The sorting brush B-1, as before is positioned to sense the cards in the column in which the "12" hole appears. In Fig. 4 as in Fig. 3 the pairs of cards 55 are indicated by double headed arrows and the direction of feed is indicated by the straight arrows. A blank card is placed in the hopper first to insure that the circuits will be properly operative when the first punched card comes under the brush B-1.

When the card designated P-1 (Fig. 4) passes under the brush B-1, the "12" hole in said card 65 will be sensed in the normal manner at the "12" index-point position of the cycle so that the sorting magnet SM will be energized when the leading edge of the card has passed beneath the ends of all but one of the blades 20, so that the P-1 card will be subsequently guided into the "12" pocket. The commutator C-1 becomes effective 70 at the "12" index-point position to establish the holding circuit of the sorting magnet SM exactly as before described, so that the card designated 75 "1" will be conveyed into the "9" pocket after

it has passed beneath the brush B-1, since the sorting magnet SM will remain energized through the first part of the cycle in which the card "1" is passing beneath the brush B-1.

It will be seen that in this case the pair of cards P-1, 1 will be split, the P-1 card going into the "12" pocket, whereas the card designated "1" will go to the "9" pocket. During the second card cycle while the card designated "1" is passing beneath the brush B-1, commutator C-2 will break the holding circuit through the magnet SM. When the card designated 2 is traversed by the brush no-hole will be encountered in the "12" index-point position and said card will be guided to the reject or "R" pocket. In a similar manner 80 the cards designated 5, 6 and 7 will be conveyed to the reject pocket, whereas the cards designated P-3, P-4 and P-8 will be conveyed to the "12" pocket and the cards designated 3 and 4 will be guided to the "9" pocket.

It will be clear, therefore, that, when a sorting operation such as just described has been completed, the single cards will be found in the reject pocket, the "P" cards will be found in the "12" pocket and the cards which are paired with the 100 "P" cards will be found in the "9" pocket.

IV. *Removing superfluous cards*

It may sometimes happen that cards are punched erroneously as, for instance, a duplicate 105 card may be punched when the invoice is paid or the group number may be punched incorrectly in one of the cards representing a paid invoice. These duplicate cards and the erroneously punched cards may be separated from the paired 110 cards under certain circumstances by a sorting operation somewhat similar to that in which the paired cards are sorted into a single pocket. In order to do this an additional control column is provided in both the "P" cards and the invoice 115 cards, in which the punching of the "12" hole is reversed.

It will be noted by reference to Figs. 3 and 4 that the cards not designated by the letter P have a "12" hole in a column different from the column 120 in which the "12" hole appears in the "P" cards, and the corresponding column in the "P" cards has no "12" hole. In order to select the superfluous cards the batch of cards is placed in the machine with face up so the cards will be fed in 125 reverse numerical order. The arrangement of the batch of cards and the manner in which they are fed is illustrated in Fig. 5 where the solid arrow represents direction of feed, while the curved solid arrows represent the true pairs, and 130 the broken curved arrows indicate a false pair caused, for instance, by incorrect punching of the group number. It will be observed that there are two P-6 cards, and that following the pair of cards designated P-5, 5 is a card designated 135 P-4, which card was accidentally punched with a wrong group number and has no corresponding card designated 4 paired with it. It will be noted from an inspection of Fig. 5 that in the present case the "P" cards follow their mates and do not precede them as is the case in Figs. 3 and 4.

The sorting brush B-1 is set to sense the column in which the "12" hole appears in the cards not designated by the letter P in Fig. 5 and the commutator C-5 is made current conducting in the "9" index-point position. When the brush B-1 senses a "12" hole in the card designated 7 in the Fig. 5, said "12" hole will be read as if it were a "9" hole in a normally fed card where the nines are read first, consequently the sorting 150

magnet will be energized immediately and the card designated 7 will be conveyed to the "9" pocket. The holding circuit will be set up through the commutator C-1 and eventually, during the 5 same cycle, the commutator C-2 will come into action to maintain said holding circuit through the first part of the following cycle in which the brush B-1 is traversing the card P-7, and the card designated P-7 will be likewise guided into the "9" pocket. Thus a true pair of cards will be 10 guided into the "9" pocket.

In similar fashion the cards P-6 and 6, respectively, will be guided into the "9" pocket and, since the first card designated P-6 has no hole 15 in the column sensed by brush B-1, the holding circuit through the sorting magnet SM will be broken by the commutator C-2. When the second P-6 card is traversed by brush B-1 no "12" hole will be encountered in the column traversed 20 by said brush, consequently the second card P-6 will be conveyed to the reject pocket. Thus, in every case where a true pair is immediately followed by a single card designated by the letter P in the drawing, the second card will go to the 25 reject pocket and this action will occur even though the second card has a different group number as is the case with the card designated P-4 which immediately follows the true pair designated P-5, 5.

Occasionally it may happen that a card is erroneously punched to represent as "paid" an invoice which has not in fact been paid or the group number may be erroneously punched so that it accidentally mates with a card representing an invoice which has not been paid. The 30 last two cases are illustrated by the pairs designated P-3, 3 and P-1, 2. The sorting machine is incapable of selecting the last mentioned pairs of cards, since for this operation the machine 35 can only sense "12" holes and the latter alone are not sufficient to distinguish cards with different group numbers when the cards accidentally happen to occur in paired relation, however, when the batch of cards is fed through the 40 tabulating machine, the automatic group control will function between the cards designated P-1, 2, and P-3 thereby causing intervening totals to be printed which will show two single items and two single totals on the printed record 45 sheet which when the record sheet is subsequently inspected will indicate to the operator of the machine that cards have accidentally become improperly mated. The combination P-3, 3 will only be detected when the printed record sheet 50 from the tabulating machine is checked with the original records or data. A tabulating machine in which a change in the group number causes a total to be printed automatically is illustrated and described in United States Letters 55 Patent No. 1,822,594 granted September 8, 1931 to Clair D. Lake.

V. Replacing certain cards in a batch by other cards

60 It is sometimes found desirable to remove certain cards in a batch and insert others in place of the cards removed. Of course this operation could be done manually by a clerk but, where the cards to be replaced are numerous and the batch 65 large, a considerable amount of time is required most of which could be saved if the operation were performed by machine. The present invention provides means for quickly and efficiently performing the foregoing operation on an ordinary sorting machine.

The new cards which are to replace others already in the batch will be provided with a "12" hole in a given column while none of the cards of the batch in which some cards are to be replaced will have a "12" hole in the column corresponding to that in which the "12" hole appears in the new cards. A preliminary sorting operation is carried out to place the cards in numerical order so that each card to be replaced will be preceded in the batch by the card which is to be 80 substituted for said card.

In order to place the cards in such order the new cards having the "12" holes are placed together in the hopper of the machine and on top of them is placed the batch of cards in which some cards are to be replaced by new cards. The combined batch of cards is then sorted in the usual fashion into numerical order according to the group number after which operation it will be found that each card to be replaced will be preceded by the card which is to replace that particular card. In other words, each of the cards which is to be replaced will be found to be paired with the corresponding new card having the "12" hole with the latter card first in sequence.

The single batch of cards is now placed in the machine hopper in the normal fashion with the first card face down, a blank card having been first placed in the hopper, so that the "9" index-point positions will be sensed first by the brush 105 B-1 and the latter is adjusted to traverse the column in which a "12" hole is likely to appear. The switch S-3 is closed, switch S-1 is placed in the upper position, and the commutator C-5 is made current conducting in the "12" position 110 only. The switches S-2 and S-4 remain open.

The sequence in which the cards are fed when the machine is started is illustrated in Fig. 6 in which the straight arrows indicate the direction of the card feed while the curved double-headed 115 arrows indicate the cards which are to be interchanged. In this figure the group numbers are shown with large numerals and the cards which are to replace others are designated by an "X" preceding the group number which indicates that 120 a card so designated is to replace the one immediately below having the same group number. Thus, the cards designated X-1, X-3, X-4 and X-7 are to replace the cards designated 1, 3, 4 and 7, respectively.

When the brush B-1 senses the "12" hole in the card X-1 a circuit will be established from line 26, the "12" position of commutator C-5, brush CB, contact roll CR, brush B-1 through the hole in the "12" index-point position of the 130 card X-1, normally closed contacts of relay R-4, windings of relays R-1, R-2, brushes 28, commutator C-3 (Current conducting at "12" index-point position of each cycle), and the normally closed lower contacts of relay R-3, to line 25.

The closure of the contacts of relay R-1, sets up a holding circuit for itself and relay R-2 which circuit is maintained for a short time after the hole in the "12" index-point position has passed brush B-1. Closure of the contacts of relay R-2 sets up a second holding circuit through commutator C-2 shortly after the "12" index-point position (Fig. 2) which circuit is maintained after the holding circuit for relay R-1 has been broken by commutator C-1. The 140 circuit through commutator C-2 is maintained until just after the "8" index-point position of the next cycle. The X-1 card will be conveyed to the "R" or "reject" pocket as the sorting magnet SM is shunted at the "12" position.

The commutator C-3 breaks the shunt in the sorting magnet SM immediately after the "12" index point position thereby causing the sorting magnet to attract its armature and lower all the blades 20. The sorting magnet remains energized until after the commutator C-2 breaks the holding circuit through relay R-2 and magnet SM just after the "8" index-point position of the following cycle, consequently the card designated 5 "1" will be conveyed to the "9" pocket. As there is no hole in the column of the card designated "1" corresponding to the column in which the "12" hole appears in the card designated X-1 the sorting magnet SM will not be energized during the cycle when said card is sensed by brush B-1. Since the card designated 10 "2" has no "12" hole the sorting magnet SM will not be energized during the cycle when said card is sensed by brush B-1, consequently 15 said card will be conveyed to the "R" pocket and will fall on top of the X-1 card.

It is clear that the "12" hole in each card designated "X" will set up a circuit which causes the card immediately following to be conveyed to the "9" pocket without affecting the progress of the card so designated to the "R" pocket and that any card not designated with an "X" and not preceded by one so designated will also be conveyed to the "R" pocket. When the sorting operation 20 is completed the cards which are to be removed and replaced will be accumulated in the "9" pocket while in the "R" pocket will accumulate a batch in which all the desired cards have been replaced by new cards. This batch of cards may be tabulated in a tabulating machine of well known construction or the removed cards may be tabulated, or both groups of cards may be tabulated separately depending on what kind of data the cards represent and the data which is desired.

It may be desired at a future date to replace other cards of a batch in which some cards have already been replaced by others so that the batch contains a number of cards having the "12" hole. In order to do so the new cards must be perforated at "12" in a column corresponding to a column in the old cards in which no "12" hole can appear. It is likely that such card replacements will occur at regular intervals, let us say monthly, in which case it will be found advantageous to assign a whole field of several columns in each card for the purpose of controlling replacements. If the cards need only be used for a year, for example, a field of twelve columns would be assigned to replacement control. In January the new cards would be made out with the "12" hole in the first column of the field for replacement control, in February the "12" hole would appear in the second column, and so on. The foregoing system ensures that the "12" holes in the old cards will not cause interference with the "12" holes in the new cards. Obviously any number of substitutions may be made within reasonable limits depending upon the capacity of the card to receive data designating perforations.

VI. Replacing certain cards and removing others in a single passage of the cards through the machine

The operations of replacing certain cards and removing others may be successfully accomplished according to the present invention during a single passage of the batch through the machine. The new cards which are to replace others already in the batch are provided, as described in the pre-

ceding section, with "12" holes in a predetermined column while for each card which is to be removed from the batch without being replaced there is provided a control card having merely the group number punched therein and a "9" hole punched in some unused column. The cards to be removed will have no perforation in the column corresponding to that in which the "9" holes appear in the control cards.

The new cards having the "12" holes are placed in the hopper first and then the control cards having the "9" holes are placed on top of the new cards. The first run of a normal sorting operation to place the cards in numerical order according to group number is then carried out. When the cards become exhausted from the hopper the old cards having no special holes are placed in the hopper and the first sorting run continued with the old cards until they in turn become exhausted. The additional runs necessary to place the cards in numerical order are then carried out as before. The combined batch of cards is now ready for the special sorting operation to replace the desired cards with new ones and also remove others without corresponding replacements.

Fig. 7 illustrates the relation between the cards after the preliminary sorting operation has been completed. It will be noted that certain cards designated by an "X" before the group number 105 are to replace those cards immediately following, that is, which are below, the cards so designated, and the "X" cards have a "12" hole in a given column as described in the preceding section. Thus, the cards X-1, X-3, and X-4 are 110 to replace the cards 1, 3 and 4, respectively. The cards designated "R" are the control cards which are to be used to remove the cards with corresponding group numbers originally present in the batch appearing immediately below the 115 cards designated with the "R". Thus, the cards designated R-2 and R-6 control removal of the cards 2 and 6, respectively, and are provided with "9" holes in a column which does not correspond to the one in which the "12" holes appear in the 120 cards X-1, X-3 and X-4. The solid straight arrows indicate the direction of feed of the cards, the solid curved arrows the cards to be interchanged, while the cards to be removed are designated by broken curved arrows.

The machine is provided with an extra brush holder and brush B-2 like the brush B-1, the latter being positioned to sense holes in the columns having the "12" hole while the brush B-2 is electrically connected to the brush B-1 and 130 is positioned to sense in the column having the "9" holes. The commutator C-5 is made current conducting in the "9" and "12" positions, switch S-3 is closed, and switch S-1 is placed in the upper position. Switches S-2 and S-4 135 remain open. A blank card is placed at the bottom of the hopper as described in preceding sections and the cards are placed face down in the hopper so the brushes B-1, B-2 will sense the "9" index-points first and the "12" index-points 140 last.

When the machine is started the blank card will go to either the reject pocket or the "9" pocket depending upon the point at which the machine stopped after a previous sorting operation. The card X-1 will be conveyed to the reject or "R" pocket since the "12" hole in said card will set up a circuit through relays R-1, R-2, and brushes 28 of commutator C-3, as described in the preceding section, and the com- 145

mutator C-2 will set up a holding circuit for the relay R-2 which will be maintained until the "8" position of the next cycle when the "1" card is being sensed. The commutator C-3 will break 5 the circuit through brushes 28 just after the "12" position, thereby causing the sorting magnet SM to become energized. The card "1" will be conveyed to the "9" pocket owing to the fact that the holding circuit through the sorting magnet 10 SM, relay R-2 and commutator C-2 is maintained until the "8" position of the cycle in which the card "1" is being sensed.

The brush B-2 next senses the "9" hole in the card R-2 so that this card will also be conveyed 15 to the "9" pocket and the sorting magnet will remain energized, due to the joint action of commutators C-1, C-2, until the card 2 is sensed, consequently, the last named card will also go to the "9" pocket and will fall on top of 20 the cards 1 and R-2. The cards X-3 and X-4 will similarly go to the "R" pocket and will fall on top of the card X-1. The cards 3 and 4 will be conveyed to the "9" pocket and will fall on top of the cards 1, R-2, and 2. The card 5, as it 25 has no "9" or "12" hole and is not preceded by a card having either a "9" or a "12" hole, will go to the reject pocket. The cards R-6, 6, like the cards R-2, 2 will be carried to the "9" pocket.

When the analysis of all the cards has been 30 completed the cards designated X-1, X-3, X-4, and 5 will be found in numerical order in the "R" pocket while the cards 1, R-2, 2, 3, 4, R-6 and 6 will likewise be in numerical order in the "9" pocket.

35 VII. Removing completed groups of cards from a batch

In the practice of accounting according to the Hollerith system record cards are often made out 40 to represent successive steps in a transaction or operation or to represent a series of transactions or operations. When the final step, transaction, or operation has taken place, a closing card is made out which cards completes the series of 45 cards previously made out and filed away among similar cards. As each series of transactions or operations becomes complete it is usually desirable to remove from the file of cards all those previously prepared cards related to each card which 50 completes a series and place the completed groups in a separate file or destroy them.

The foregoing may be illustrated by a specific example. When goods are sold on the installment plan a card is perforated to represent the 55 invoice of goods shipped and contains the necessary data as to the conditions of sale, price, and so on. As each invoice is paid a closing card is made out to match the original card representing the invoice and other cards may also 60 be made out to represent installment payments in the interval of time between the shipping of the goods and the final or closing payment. When the final payment is made completing the 65 transaction between seller and buyer it is desirable to remove those cards representing closed transactions so that the remaining cards can be passed through the tabulating machine for the purpose of preparing dunning statements to delinquent debtors.

70 It is ordinarily necessary to remove the completed groups of cards manually, an operation which requires the expenditure of considerable time and labor much of which could be saved if the operation could be performed mechanical- 75 ly. The present invention has been so devised

as to permit the foregoing operation to be quickly performed on a well known form of sorting machine with a consequent saving of time and labor.

The cards representing invoices of goods shipped are provided with "11" holes in a given column while the cards representing payment in full or the final payment are provided with "12" holes in the column corresponding to that in which the "11" hole appears in the cards representing invoices. The cards representing intervening installment payments are not provided with either "11" or "12" holes in the column in which the latter appear in the other cards.

As a preliminary, the cards representing invoices, installment payments, and final payments are sorted together into numerical order according to group number or invoice number after the fashion described in preceding sections so that all the cards of a given group number are together with the card having "11" hole last, the card having the "12" holes first, and the cards having no hole in between.

The cards of the batch thus secured are placed 100 face down in the hopper of the machine, a blank card having first been placed at the bottom of the hopper as in preceding sections, so that the brush B-1 will read the "12" index-point positions first, thus the "12" holes will be 105 sensed as if they were "9" holes and the "11" holes as "8" holes.

The brush B-1 is positioned to sense in the column in which the "11" card "12" holes appear, the commutator C-5 is made current conducting in the "9" and "8" positions, switches S-2, S-4 are closed, and the switch S-1 is placed in its upper position. The switch S-3 remains open.

Fig. 8 illustrates the direction of feed and arrangement of a batch of cards from which completed groups are to be removed and conveyed to a pocket separate from the incomplete groups. The solid straight arrows represent the direction of feed, the solid curved arrows the completed 115 groups, and the broken arrows the incomplete groups. The letter "P" before the group number represents an installment payment "FP", a payment in full or a final installment payment, and "I" an invoice. The pairs of cards P-1, I-1 120 and P-5, I-5 represent invoices on which one installment payment has been made, the pair FP-2, I-2 an invoice paid in full. The single card I-3 stands for an unpaid invoice while the group FP-4, P-4, P-4, I-4 illustrates a 125 complete group of cards representing an invoice paid in three installments. The groups FP-2, I-2 and FP-4 . . . I-4 are to be sorted into a pocket separate from the others.

The first card P-1 has neither an "11" nor a 130 "12" hole and hence will be conveyed to the reject pocket. The "11" hole in the card I-1 is sensed as if it were an "8" hole and, as the commutator C-4 is effective at the "8" position in the cycle a circuit will be established through 140 relay R-3 causing the upper contacts thereof to close to establish a holding circuit for said relay through commutator C-1 and at the same time causing the lower contacts of said relay to open thereby breaking the circuit through the sorting 145 magnet SM. The relay R-3 is designed to operate more quickly than the sorting magnet SM so as to prevent the latter from being energized over the normal sorting circuit from brush B-1 through relays R-1, R-2. The card I-1 will 150

be conveyed to the reject pocket since the magnet SM is not energized. At the end of the cycle the commutator C-1 will break the holding circuit through relay R-3.

5 The brush B-1 next senses the "12" hole in card FP-2 at the "9" position in the cycle thereby energizing the sorting magnet SM and causing the card FP-2 to be conveyed to the "9" pocket. A holding circuit for sorting magnet SM 10 and relays R-2, R-4 is set up through the normally open contacts of relay R-2 now closed which circuit is maintained until the brush B-1 senses the "11" hole in card I-2 at the "8" point in the cycle thereby establishing a circuit through relay R-3 and commutator C-4 as previously described which holding circuit is held through the commutator C-1 until the end of the cycle. The relay R-3 opens its contacts and breaks the circuit through the sorting magnet SM and relays R-2, R-4 so that the card I-2 will be conveyed to the "9" pocket.

15 The card I-3 will be treated like the card I-1 as the "11" hole therein has no effect except to prevent energization of the sorting magnet and 20 consequently the card I-3 will likewise be carried to the reject pocket.

25 The card FP-4, due to the "12" hole therein, will set up the holding circuit through the sorting magnet SM and will be conveyed to the "9" pocket. The two cards P-4 and the card I-4 30 will likewise be conveyed to the "9" pocket and, during the sensing of card I-4, the presence of the "11" hole therein will cause the holding circuit through the sorting magnet SM to be broken.

35 After the sorting operation has been finished all completed groups of cards like the groups FP-2, I-2 and FP-4 . . . I-4 will be accumulated in the "9" pocket while the other cards will be together in the reject or "R" pocket.

40 Several illustrative operations have been described herein to show the adaptability of the invention to the solution of various practical problems. It will be understood of course that the invention is useful in other cases where it is necessary to pair, exchange or replace, or remove cards, or remove whole groups comprising more than two cards, and is not limited to the specific examples selected for purposes of illustration.

45 Nor is the invention limited to the specific form or arrangement of parts and circuits illustrated and described as various changes may be made to adapt the invention to the varying conditions found in practical applications without in anywise departing from the principles described herein and illustrated in the drawings.

I claim:

50 1. A sorting machine adapted to sort a batch of records wherein occur pairs of records interspersed by single records, the leading record of a pair being provided with a designation having a predetermined value signifying that the leading record and the record following form a pair, comprising sorting mechanism adapted to distribute records according to the value of designations in the records, a circuit for controlling said mechanism, a single record sensing brush controlling said circuit in accordance with said 55 designations when the latter are sensed by said brush, an auxiliary device operative to control said circuit to cause an invariable distribution of records which follow those having designations indicating pairs, such distribution being always the same regardless of the value of the designation indicating a pair, and means controlled by

said brush for calling into operation said device whenever said brush senses the designation indicating a pair.

5 2. A sorting machine adapted to be controlled by a batch of records in which occur pairs of records interspersed by single unpaired records, said pairs of records being distinguished by a single control designation in one of the records of each pair, comprising sorting mechanism, a circuit for controlling said mechanism, a single sorting brush in said circuit and adapted to sense said control designation, a commutator device adapted to prevent the sorting circuit from being effective when the control designation in a record of a pair is sensed whereby to determine a given destination for the designated records, a second commutator device adapted to control the sorting circuit to determine a different destination for the undesignated records of the pairs, and means controlled by the sensing brush for rendering the second commutator device effective.

10 3. A sorting machine adapted to be controlled by a batch of records wherein occur paired records interspersed by single unpaired records, the paired records being distinguished by a predetermined control designation in one of the records of each pair, the other record of each pair being undesignated; comprising sorting mechanism, a single record sensing element for controlling the sorting mechanism according to the value of the control designations in the records, an auxiliary device operative to render the sorting mechanism ineffective to sort records with respect to the value of the predetermined control designation only whereby to cause the records having such designation to be rejected, and means called into operation by the sensing element when the latter senses said predetermined designations for controlling the sorting mechanism to determine a common and separate destination for the un- 110 designated records of the pairs.

15 4. A sorting machine adapted to be controlled by a batch of records wherein may occur together pairs of records which are related to each other and identified as pairs by a designation of predetermined value in one of the records of each pair; comprising a record sensing element adapted to detect the presence of such designation in a record when the records are presented to said element in such order that each record bearing such designation is sensed prior to sensing of the other records of the pairs, sorting mechanism controlled by said element and normally effective to distribute the records according to the value of designations in the records, an auxiliary device 130 normally effective to render the sorting mechanism ineffective to sort in the normal manner when the sensing element detects the presence of the designation identifying a pair of records whereby to cause the sorting mechanism to reject all records having such designation, and means controlled by the sensing element and effective to determine a predetermined and common distribution of the undesignated records of the pairs subsequent to the rejection of the designated records whereby to effect a distribution of the undesignated records of the pairs different from the distribution of the designated records of the pairs.

20 5. A sorting machine adapted to be controlled by a batch of records wherein certain related records occur together in pairs which pairs may be interspersed by single unrelated undesignated records, said pairs being identified by a control designation having a predetermined value in one 150

of the records of each pair; comprising a single electric sensing element adapted to detect the presence of such control designations in a record, mechanism adapted to distribute records according to the value of data designations in such records including a control circuit connected to said element, said mechanism being normally effective to reject undesignated records and operative to dispose of the designated records of the 10 pairs in accordance with the control designation identifying the pairs; a switching device connected to said circuit and operative to modify the action of the sorting mechanism whereby to determine a disposition of the undesignated records of the pairs different from the disposition of the designated records of the pairs and the single undesignated records, and means controlled by the sensing element for rendering said switching device effective subsequent to the sensing of a designated record of a pair.
